[57] ABSTRACT

A door closing system for a door supported for movement along a predetermined path. An elongated ten-

sion member is length-wise disposed along the path of movement of the door for longitudinal shifting and a fusible anchor is operatively associated with the tension member to anchor it against movement in a first lengthwise direction. A spring mechanism is operatively associated with the anchor member and yieldingly biases the same in the aforementioned first direction. The door includes a follower guidingly engaged with the tension member for movement therealong and the door is shiftable in the aforementioned first direction to a closed position and in the opposite direction to an open position. An abutment is carried by the tension member on the side of the follower opposite to the aforementioned first direction when the door is in the open position and the spring structure biasing the tension member in the first direction is operatively connected thereto at a point spaced in the first direction from the follower of the door when the door is in its closed position, the abutment or enlargement carried by the tension member being abuttingly engagable with the follower of the door upon movement of the tension member in the first direction whenever the door is shifted from its closed position toward its open position in order to transfer the biasing action of the spring structure to the door through the follower so as to bias the door to its closed position upon melting of the fusible anchor.

FIRE DOOR CLOSING SYSTEM

The fire door closing system of the instant invention has been designed to overcome some of the objectionable operating characteristics of presently available fire door closing systems. Present systems utilizing fusible links or anchors are constructed in a manner whereby manual operation of the associated fire door, as occasionally is desired, results in at least partial operation of the automatic fire door closing system. Although proper operation of such automatic fire door closing systems is not always impaired by previous manual opening and closing of the associated fire door, damage to the fire door closing system can occur, at least in some instances. Further, previous fire door closing systems constructed in a manner necessitating at least partial operation of the door closing system as a result of manual shifting of the associated fire door cannot be inspected by regulatory agencies periodically with those regulatory agencies knowing that the fire door closing system will not in any way be actuated until actuated by a fire. Therefore, proper inspection and control over present day fire door closing systems may not be carried out.

However, the fire door closing system of the instant invention is constructed in a manner whereby manual opening and closing of the associated fire door in no way actuates any portion of the fire door closing system. In this manner, the system, between periodic checks by regulatory agencies, remains inactive instantaneously ready for proper actuation in the event of a fire.

Further, the fire door closing system of the instant invention is quite simple in design and relies upon only a tension member, a fusible anchor and a spring mechanism operatively connected to the tension member for full and complete operation.

The main object of this invention is to provide a fire door closing system which will, in the event of sensing heat associated with a fire be automatically actuated to close an associated fire door.

Another object of this invention, in accordance with the immediately preceding object, is to provide a fire door closing system operatively associated with the corresponding fire door in such a manner so that the fire door closing system may be maintained totally inactive during manual opening and closing of the fire door.

A still further object of this invention is to provide a fire door closing system which may be readily attached to substantially all types of fire doors.

A final object of this invention to be specifically enumerated herein is to provide a fire door closing system which will conform to conventional forms of manufacture, be of simple construction and automatic in operation so as to provide a device that will be economically feasible, long lasting and relatively trouble free.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is an elevational view of a typical type of sliding fire door with the fire door closing system of the instant invention operatively associated therewith;

FIG. 2 is an enlarged fragmentary perspective view of the fire door closing system in operation sliding the associated fire door toward a closed position; and

FIG. 3 is an enlarged fragmentary perspective view illustrating the tension member guide pulley of the fire door closing system and its mounting bracket in operative association with the corresponding fire door and door mounting track.

Referring now more specifically to the drawings the numeral 10 generally designates a wall structure having a door opening 12 formed therein. An elongated generally horizontal support and guide track 14 is supported from the wall structure 10 and a horizontally shiftable fire door 16 is guidingly supported from the support and guide track 14 by means of upstanding followers 18 of conventional design supported from the upper marginal edge portion of the door 16 and guidingly engaged with the support and guide track 14.

The support and guide track 14 is substantially horizontal and accordingly, although the door 16 is supported from the track 14 by means of anti-friction followers, the door 16 tends to remain in any position disposed along the guide track 14 in which it is placed.

The fire door closing system of the instant invention is referred to in general by the reference numeral 20 and includes a spring loaded winding drum assembly referred to in general by the reference numeral 22 journaled from a mounting bracket 24 anchored to the wall structure 10 by means of suitable fasteners 26. The system 20 further includes a Z-shaped mounting bracket 34 including a short upper vertical flange 30 secured to the wall structure 10 by means of suitable fasteners 32 and a longer depending lower vertical flange 34 supported from the lower end portion of the upper flange 30 in laterally offset relation relative thereto by means of a connecting horizontal flange 36. The lower end of the lower flange 34 has a guide pulley 38 journaled therefrom and the guide pulley 38 is disposed on the side of the door opening 12 remote from the side thereof on which the winding drum assembly 22 is disposed. Further, the upper periphery of the guide pulley 38 is disposed along a line tangent to the upper peripheral portion of the winding drum assembly 20 and parallel to the support and guide track 14.

One end of an elongated flexible tension member 40 is anchored to the winding drum assembly for winding thereon and the other end portion of the tension member 40 is trained over the guide pulley 38 and extends back toward the winding drum assembly 22 and is anchored to the wall structure 10 adjacent the mounting bracket 24 as at 42. Further, the tension member 40 includes a fusible link 44 and accordingly the fusible link 44 and that portion of the tension member 40 extending between the fusible link 44 and the anchor point 42 comprises a fusible anchor connection for the end of the tension member 40 remote from the winding drum assembly 22.

The winding drum assembly 22 may be of any conventional spring loaded type and the spring structure (not shown) thereof yieldingly biases the winding drum assembly 22 in an counter clockwise direction as viewed in FIGS. 1 and 2 of the drawings. Accordingly, should the fusible link 44 be melted, the spring structure of the winding drum assembly 22 will cause counterclockwise rotation of the latter in order to wind the tension member 40 thereon.

The fire door closing system 20 further includes a follow up bracket 46 secured to the end of the upper marginal edge portion of the door 16 adjacent the winding drum assembly 22 and the follow up bracket 46 includes an outstanding flange 48 provided with a horizontal bore 50 through which the tensioned tension member is loosely received.

The tension member 40 has a large diameter abutment 52 thereon secured in position in any convenient manner against shifting longitudinally of the tension member and the abutment 52 is disposed between the flange 48 and the guide pulley 38 when the door 16 is in the open position thereof illustrated in FIG. 1 of the drawings.

In operation, inasmuch as the upper reach of the tension member 40 parallels the support and guide track 14 and the tension member 40 is loosely received through the bore 50, the door 16 may be manually shifted between the open position thereof illustrated in FIG. 1 of the drawings and a closed position with the door 16 shifted to the left as viewed in FIG. 1 of the drawings in registry with the door opening 12. During movement of the door 16 between the open and closed positions the fire door closing system 20 is totally inactive in that the edges of the flange 48 defining the bore 50 need not even touch the tension member 40. On the other hand, should the fusible link 44 be subjected to sufficient heat to melt the link 44 such as would be the case in the event of a fire in close proximity to the link 44, as a result of the link 44 being melted the tension member 40 is released from its anchor to the wall structure 10 and the spring loaded winding drum assembly winds the tension member 40 thereon with the result that the abutment 52 is shifted toward the winding drum assembly 22 and abuts the face of the flange 48 remote from the winding drum assembly 22 thereby enabling the winding drum assembly 22 to slide the door 16 along the support and guide track 14 to the left as viewed in FIG. 1 of the drawings until the door 16 reaches its closed position. Thus, although the fire door closing system is maintained totally inactive during manual opening and closing of the door 16, it is maintained in a constant ready state to close the door 16 in the event of a fire. By this operation, the fire door closing system 20 may be periodically checked by the proper authorities and after being checked the system 20 will be maintained in constant readiness for automatic operation in the event of a fire although the door 16 may be manually shifted between the open and closed positions without operation of any portion of the fire door closing system.

Further, in order to prevent the abutment 52 from impacting too sharply with the flange 48, a coiled compression spring 56 is loosely disposed on the tension member 40 intermediate the flange 48 and the abutment 52. Accordingly, should the door 16 be disposed in a partially closed position when the fusible link 44 melts and releases the tension member 40 for rapid winding on the spring loaded winding drum assembly 22, impact of the abutment member with the flange 48

will be cushioned by the spring 56.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows:

1. In combination with a building structure having a doorway therein and a fire door supported adjacent one side of said doorway for general horizontal shifting to a closed position in registry with said doorway, an elongated tension member generally paralleling the path of movement of said door between its open and closed positions and extending between the opposite sides of said doorway, said tension member being supported for longitudinal shifting, force means connected to said tension member on the other side of said doorway yieldingly biasing said tension member in a lengthwise direction to said other side of said doorway from said one side thereof, a follower supported from said door and movable along said tension member in close proximity thereto during shifting of said door between said open and closed positions, an abutment carried by said tension member on the side of said follower remote from said other side of said doorway and engagable with said follower upon shifting of said tension member toward said other side of said doorway to thus shift said door from the open position thereof to the closed position thereof, and releasable anchor means attached to said tension member for preventing longitudinal shifting thereof toward said other side of said doorway under the biasing action of said force means, said releasable anchor means including a fusible portion thereof which will melt, and thereby release said elongated tension member for movement under the biasing of said force means, in response to being subjected to sufficient heat, said tension member comprising an elongated flexible member, said force means comprising a spring bias winding drum supported at said one side of said doorway and to which the adjacent end portion of said tension member is attached for winding thereon, a guide pulley supported from the other side of said doorway and about which the other end portion of said tension member is passed said releasable anchor means serving to anchor the end portion of said tension member passed about said guide pulley to said one side of said doorway, said follower comprising an outstanding flange carried by said door having an opening formed therethrough through which the reach of said tension member extending from said winding drum to said guide pulley is loosely received, said abutment being mounted on said tension member between said flange and said guide pulley.
2. The combination of claim 1 including a coiled compression spring loosely disposed on said tension member intermediate said follower and abutment means.
